UNITED STATES PATENT OFFICE.

ALMEDA M. PERRAULT, OF POUGHKEEPSIE, NEW YORK.

DESIGN FOR A BOTTLE.

No. 39,856.

Specification for Design.

Patented March 2, 1909.

Application filed December 23, 1908. Serial No. 469,033. Term of patent 7 years.

To all whom it may concern:

Be it known that I, ALMEDA M. PERRAULT, a citizen of the United States, residing at Poughkeepsie, in the county of Dutchess and State of New York, have invented a new, original, and ornamental Design for Bottles, of which the following is a specification, reference being had to the accompanying drawing, forming part thereof.

The figure is an elevation of a bottle showing my new design.

The essential feature of my new design is a figure of a serpent in relief on and extending around the outer surface of the bottle.

I claim:

The ornamental design for a bottle as shown and described.
